WITNESS:

UNITED STATES PATENT OFFICE.

SAMUEL McCARDIA, OF STRATHCONA, CANADA.

FLY-PAPER HOLDER.

Application filed October 18, 1921. Serial No. 508,589.

To all whom it may concern:

Be it known that I, SAMUEL McCARDIA, a British subject, residing at Strathcona, in the Province of Alberta and Dominion of Canada, have invented new and useful Improvements in Fly-Paper Holders, of which the following is a specification.

My present invention has reference to a fly paper holder.

10 My object is to produce a simple means whereby a sheet of fly paper will be effectively supported in an outward arched condition, so that all the sticky surfaces thereof will be exposed.

15 A further object is to produce a holder for fly paper wherein the paper may be secured on the holder and supported at an upward arch with respect thereto, without danger or liability of the hands of the person applying the paper coming in contact with the sticky surface thereof.

It is a still further object to produce a holder for fly paper in the nature of a plate that is slotted, in a peculiar manner, adjacent to the ends thereof, whereby the metal bounded by the slits may be rounded upwardly and outwardly to form arched spring pointed fingers, the pointed ends of which are designed to be passed through the non-covered edges of a fly paper, and the said fingers supporting the fly paper at an upward arched condition.

It is a still further object to produce a holder for fly paper that has, adjacent to its ends spaced pairs of curved fingers that terminate in points, the body of the device, below said points having openings whereby the non-treated edges of a fly paper may be arranged thereover, and the fingers forced therethrough and through the openings, the said fingers being then permitted to spring to their initial positions for holding the fly paper at an upward arch with respect to the support.

45 The foregoing, and other objects which will appear as the nature of the invention is better understood, may be accomplished by a construction, combination and operative arrangement of parts, such as is disclosed by the drawings which accompany and which form part of this application.

In the drawings:—

Figure 1 is a plan view of the blank from which the improved holder is formed.

55 Figure 2 is a similar view but showing the metal bounded by the slotted portions

bent to provide pointed curved fingers which are attached to and support thereon the fly paper.

Figure 3 is a sectional view approximately 60 on the line 3—3 of Figure 2.

Figure 4 is an end view showing the fly paper attached.

Figure 5 is an edge view with the fly paper in supported position. 65

Figure 6 is a plan view thereof.

As disclosed in Figure 1 of the drawings, my improved holder comprises a flat plate of any desired material with an inherent resiliency. The plate is indicated by the numeral 1, and preferably has its outer edges flanged upwardly as at 2. Thus the plate is really in the nature of a pan, and the said plate, adjacent to the ends thereof is at spaced points equi-distantly from the center thereof slotted transversely as at 3—3 and from thence diagonally as at 4 from one of the terminals of one of the slits 3 to the terminal of the opposed slit 3. The metal bounded by these slits is rounded upwardly 70 over the plate proper to provide arched spring fingers 5 respectively. These fingers have their ends pointed so that the same will readily enter the non-treated edges of a fly paper 6. 75

In line with the pointed downturned edges of the fingers 5, the plate 1 is provided with rounded openings 7, and the inner walls of these openings are formed with depending flanges 8. The flanges, in addition to 80 lengthening the openings which they surround, serve as legs or supports for the body plate 1.

In applying the paper 6 to the holder, one of the non-treated edges thereof is arranged 85 on the body plate 1, over two of the openings 8 adjacent to the ends of the device. The curved spring fingers 5 arranged thereabove are now forced downwardly through the edge of the paper and through the openings 8. The pointed ends of the fingers passing through the paper hold the paper thereon, the said fingers being gradually increased in width from their points cannot enter the paper beyond a predetermined 100 degree. Next the opposite non-treated edge of the paper is arranged beneath the opposite pairs of fingers over the openings, and these fingers are then pressed through the paper and through the openings as above 105 described. The opposed pairs of fingers, when released, will spring outwardly, that 110

is the points thereof will spring toward the edges of the body plate 1, and in so doing will hold the paper 6 in an upwardly arched condition. My improvement may be successfully employed in kitchens of hotels, restaurants, dwelling houses, or any place where flies are liable to enter, and from experience I have found that while flies are primarily attracted in such places by the odor of the food and cooking thereof, the flies will light on a painting or reproduction of such produce. Considering this, I intend to provide the outer face of the fly paper 6 with a representation of varying products which are sold in different establishments, as for instance, vegetables, meats, flowers, etc. In addition to providing a means for more effectively attracting the flies, such representation on the coated face of the fly paper will render the same more pleasing to the human eye, and as the paper may have suitable indicia thereon it can be successfully employed as advertising means. In addition to this, the paper may have imprinted on the back thereof instructions regarding the application of the said paper to the holder.

It is thought that the foregoing description, when taken in connection with the drawings will fully set forth the construction and advantages of the improvement to those skilled in the art to which such inventions relate, it being, of course, understood that such changes may be made from the showing and description as fall within the scope of what is claimed.

Having described the invention, I claim:—

1. In a fly paper holder, a body plate, and upwardly extending oppositely directed rounded pairs of plate engaging fingers adjacent to the ends of said plate.

2. In a fly paper holder, a body plate, upwardly arched downwardly extending fingers arranged in spaced pairs on said plate, and said fingers gradually increasing in width from the outer and pointed ends thereof. 45

3. A fly paper holder, comprising a flat body plate, curved fingers arranged in pairs on said plate, said fingers being V-shaped in plan, and said plate having openings arranged beneath the pointed ends of the fingers. 50

4. A fly paper holder, comprising a flat body plate, curved fingers arranged in pairs on said plate, said fingers being V-shaped in plan, and said plate having openings arranged beneath the pointed ends of the fingers, and flanges surrounding and depending from said openings providing feet for the plate. 55 60

5. In a fly paper holder, a plate having upwardly extending flanges on the outer surfaces thereof, upwardly projected rounded fingers arranged in spaced pairs adjacent to the ends of the plate, said fingers having pointed ends which are disposed in comparatively close relation with respect to the body plate, said body plate having openings below and in a line with the fingers, and depending flanges surrounding said openings. 65 70

6. A fly paper holder constructed from a plate of material having an inherent resiliency, said plate, adjacent its ends having spaced transverse slits, and a diagonal slit between and terminating in a line with the terminals of said parallel slits, the material between the slits being bent upwardly and rounded outwardly and downwardly to provide spaced fingers which engage with the fly paper. 75 80

In testimony whereof I affix my signature.
SAMUEL McCARDIA.
